1971, Ser. No. 203,392

Term of patent 14 years

Int. Cl. D24—99

U.S. Cl. D83—8

FIG. 1 is a front elevation of a retractile clip-on pacifier showing my new design;

FIG. 2 is a side elevation thereof, with the retractile partially broken away and shown in cross-section for clarity of illustration;

FIG. 3 is an elevation as seen in the direction of line 3—3 of FIG. 2;

FIG. 4 is a plan view as seen in the direction of line 4—4 of FIG. 1;

FIG. 5 is a cross-section taken on line 5—5 of FIG. 2.

This is a continuation-in-part of design application Ser. No. D. 24,269, filed Aug. 3, 1970, and now abandoned.

I claim:

The ornamental design for a retractile clip-on pacifier, as shown and described.
